(57) **CLAIM**

The ornamental design for a “golf ball display case”, as shown and described.

DESCRIPTION

FIG. 1 is a front top perspective view of a “golf ball display case” showing my new design;

FIG. 2 is a front elevational view thereof, the rear and side elevational views being identical thereto;

FIG. 3 is a top plan view thereof;

FIG. 4 is a bottom plan view thereof;

FIG. 5 is a bottom perspective view thereof showing a golf ball being displayed therein; and,

FIG. 6 is a perspective view showing a golf ball displayed therein.

The broken line showing of a golf ball is for environmental purposes only and forms no part of the claimed design.
